MACHINE FOR APPLYING REINFORCING MATERIAL TO SHOE UPPERS

Donald J. T. Hamm, Ipswich, Mass., assignor to United
Shoe Machinery Corporation, Flemington, N.J., and
Boston, Mass., a corporation of New Jersey

Filed Dec. 20, 1966, Ser. No. 5,127

Term of patent 14 years

(Cl. D55—1)

Fig. 1

Fig. 2

Fig. 3

Fig. 4

Fig. 5

Fig. 6

FIGURE 1 is a front elevation of a machine for applying reinforcing material to shoe uppers showing my new design;

FIG. 2 is a top plan view thereof;
 FIG. 3 is a left-hand perspective view of the machine;
 FIG. 4 is a rear elevational view of the machine, and
 FIGS. 5 and 6 are left and right end elevational views,
 respectively, of the machine.

I claim:

The ornamental design for a machine for applying reinforcing material to shoe uppers, substantially as shown.
